PULPWOOD GRINDING APPARATUS
Lloyd Hornbostel, Beloit, Wis., assignor to Beloit Iron
Works, Beloit, Wis., a corporation of Wisconsin
Filed Dec. 31, 1959, Ser. No. 863,295
2 Claims. (Cl. 241—280)

The present invention relates broadly to the art of pulp production, and is more particularly concerned with novel method and apparatus for grinding pulpwood featuring movement of a pulp stone and pocket relative to one another, whereby there is obtained pulp of consistently uniform quality at substantial power economies.

Since the advent of the early pulpwood grinders using jackscrews and a car jack for maintaining pressure and down to the modern high production magazine grinders and continuous grinders of the ring or chain feed types, it has been found difficult to produce consistently uniform pulp. One explanation for this is the great number of variables in the pulping process, and among those of considerable importance are the sharpness of the pulp stone, the moisture content of the pulp wood and the pulpwood density.

To explain, an accepted control used in the manufacture of pulp is "freeness" or measurement of the drainage characteristics. Since all pulp is at one time in a suspended form, in order to make a sheet of paper the water must be removed, and the ease or lack of ease with which this mixture, or slurry, will drain is referred to as freeness or slowness. A free stock is usually composed of relatively long, coarse fibers, or is a stock from which the fines or flours (gelatinous bits of fractured fibers) have been removed; while a slow stock generally consists of short, fine, well-fibrillated fibers intermixed with fines. Now, in pulp grinding, freeness changes markedly from the time of sharpening the pulp stone until sharpening is again required. The sharp stone tends to cut the fibers and decrease the fines, whereas as the stone becomes worn, the extent of cutting decreases and the rubbing and refining action has the effect of producing more fines and greater fibrillation.

The variable of pulpwood moisture content bears importantly on the efficiency of the pulping operation, since when the wood is relatively wet the fibers separate more easily, their strength is greater and the power consumption is lower. While efforts are made by soaking or like procedures to have at least 30% moisture content, it is apparent that this condition cannot always be attained and a uniform moisture content for a particular load of pulpwood cannot be efficiently accomplished, even when pre-soaking is used.

Accordingly, to compensate for moisture content and density variations, while striving for consistently uniform pulp quality, the grinding pressure or unit loading is adjusted or varied. The pulpwood pocket, however, of the prior art presents a relatively large contact area both arcuately and axially, and the power requirements to vary the loading are therefore substantial. As is known, the efficiency of the pulping process is expressed in terms of horsepower per daily ton of fiber, and it can therefore be seen that when wide variations in grinding pressure or load required to obtain optimum unit loading for consistent pulp quality are necessary, the pulping efficiency is substantially diminished.

It is accordingly an important aim of the present invention to provide method and apparatus for pulpwood grinding productive of uniformly consistent pulp quality at minimum power requirements.

Another object of this invention lies in the provision of improved structures and procedures for producing pulp, wherein the pulp stone and pocket are moved relative to one another to vary the contact area of said stone

2

in abrasive engagement with pulpwood supported by said pocket, producing as among the advantages reduced stone wear.

Another object of the instant invention is to provide apparatus for grinding pulpwood to obtain pulp therefrom, comprising a rotatable grinding member, a housing for pulpwood positioned adjacent said grinding member, force applying means for advancing said pulpwood into grinding contact with said grinding member, and means for effecting relative movement between said grinding member and housing to vary the contact area of said member in abrasive engagement with said pulpwood, whereby frequency of sharpening of said grinding member and the magnitude of grinding pressure variations to attain quality control are reduced.

A further object of the invention lies in the provision of a method of grinding pulpwood, which comprises advancing a plurality of pulpwood sticks into abrasive engagement with a rotatable grind member.

Other objects and advantages of the invention will become more apparent during the course of the following description, particularly when taken in connection with the accompanying drawings.

In the drawings, wherein like numerals designate like parts throughout the same:

FIGURE 1 is a top plan view of the apparatus effective to practice the instant method, and incorporating a conical grinding member and a pulpwood pocket which is moved laterally with respect thereto;

FIGURE 2 is a fragmentary end view to illustrate the grinding action on a pulpwood stick at the relatively larger radius of the conical pulp stone of FIGURE 1; and

FIGURE 3 is a view similar to FIGURE 2 and showing the grinding action at the relatively smaller radius of the conical grinder stone.

As earlier stated, it has been difficult in the past to obtain consistently uniform pulp quality at reasonable power expenditures, due to the greater number of variables involved in the pulpwood grinding process. The freeness or measurement of pulp drainage characteristics changes substantially from the time of stone sharpening until it again becomes necessary to sharpen said stone, since it is now known that a sharp stone tends to cut the fibers and decrease the fines, whereas as the stone becomes worn, the amount of cutting decreases and the rubbing and refining action tends to increase, producing more fines and greater fibrillation. On the other hand, the variations in pulpwood moisture content and density require that the grinding pressure or unit loading be varied, and by reason of the relatively great contact area of the conventional grinder pocket, wide pressure variations or large changes in loading are necessary. This markedly increases the total power requirements for the grinding process, and a point is approached at which mechanical pulp grinding loses some of its economical attractiveness.

It has now been discovered that uniformly consistent pulp quality at minimum power expenditures is obtained by varying the contact area of the pulp stone and pulpwood relative to one another, so that pulp stone wear is reduced and the stone remains in relatively sharp condition for a longer period, and thereby continues to cut rather than rub the fibers.

The relative movement described can be accomplished by moving the grinder pocket laterally with respect to a generally conical grinder stone, or in other ways which will become immediately apparent to those skilled in the art upon a consideration of the instant disclosure.

The apparatus is illustrated in FIGURE 1 and is designated therein generally by the numeral 70. As shown,

there is provided a pulp stone or grinding member 71 of generally frusto-conical configuration supported for rotation at opposite ends by shaft means 72—72a journaled in bearing means 73—73a, respectively, said pulp stone 71 being driven in rotation by motor means or the like 74 having shaft means 75 coupled at 76 to shaft means 77 received in the bearing means 73a.

To vary the grinding contact area, a grinder pocket or housing 78 is provided with guide means 79 received in track means 80 disposed generally parallel to the grinding surface of the conical grinder 71. The pocket 78 is laterally reciprocable along the track 80 and suitable motive means for this purpose may take the form of a double acting cylinder 81 having ports 82 and 83 admitting pressurized fluid to opposite sides of a piston 84 having a rod portion 84a connected either directly to the grinder pocket 78 or to the guide means 79 thereon. Pulpwood (not shown) in the pocket 78 is urged into abrasive engagement with the conical grinder 71 by means shown in FIGURE 1 as comprising a cylinder 85 provided with ports 86 and 87 to reciprocate a piston 88 with arm portion 88a connected to plate means 89 bearing against the pulpwood sticks.

During lateral movement of the grinder pocket 78 along the track 80, the pulpwood sticks in the pocket 78 are continuously subjected to a changing stone radius, in the manner indicated in FIGURES 2 and 3. The pulp stone 71 has a relatively large radius end 71a and a relatively smaller radius end 71b between which the pulpwood sticks continuously travel under action of the motive means 81 for the grinder pocket 78. By reason of the continuously changing grinding surface in abrasive engagement with the pulwood, no single area or band along the pulp stone is subjected to greater wear, and the stone 71 accordingly longer retains a good "tooth" and the fibers from the pulwood are cut, rather than rubbed, so that a minimum amount of fines are produced. It may be observed upon reference to FIGURE 1 that a relatively small pocket 78 is utilized, presenting to the changing grinding radius a relatively smaller contact area than has heretofore been employed with the result that not only is the sharpening period prolonged, but the power requirements to maintain the optimum unit loading or grinding pressure at the nip is markedly less than has previously been the practice.

It is apparent from the foregoing description that simultaneous movement of the grinder member and pulpwood sticks relative to one another can be accomplished in numerous ways utilizing various structures. The ground pulp is of course collected in any convenient manner, and thereafter subjected to conventional processing steps. The apparatus disclosed functions effectively on all known wood employed for mechanical pulping, and customary pre-treatment may be utilized as desired. In substitution for generally flat grinding surfaces lying

parallel with the pocket and sticks being abraded, convoluted pulp stones may of course be employed and in this case the motion of the pocket can be relatively slower and the power requirements would of course be reduced. 5 This and other variations and modifications, including the use of more than a single grinder pocket for each pulp stone, may of course be practiced without departing from the novel concepts of the present invention.

I claim as my invention:

1. Apparatus for grinding pulpwood to obtain pulp therefrom, comprising a generally frusto-conical grinding member, means for rotating said grinding member, a housing for pulpwood positioned adjacent said grinding member, force applying means connected to said housing for advancing said pulpwood into grinding contact with said grinding member, track means disposed generally parallel to the surface of said grinding member and receiving said housing for movement therealong, and motive means reciprocating said housing along the track means and laterally with respect to said grinding member to vary the location of grinding contact of said member with said pulpwood, whereby frequency of sharpening of said grinding member and the power requirements to effect grinding are reduced.

2. A pulpwood grinding mechanism comprising in combination a grinding rotor having a generally frusto-conical grinding surface, rotating driving means for driving the rotor in rotation about its axis, a support for pulpwood adjacent said grinding surface for holding pulpwood in grinding contact with a portion of the length of said surface, means operatively associated with said support for moving said pulpwood support toward the surface to hold the pulpwood in grinding contact, and linear drive means operatively associated with said support relatively moving the support in a general axial direction parallel to the grinding surface to progressively change the axial location of grinding contact between the pulpwood and grinding surface whereby the pulpwood progressively engages areas of the grinding surface of changing diameter.
